CYLINDER LOCK

Edward N. Jacobi, Milwaukee, Wis., assignor to
 Briggs & Stratton Corporation, Milwaukee,
 Wis., a corporation of Delaware

Application June 5, 1936, Serial No. 83,677

6 Claims. (Cl. 70—368)

It is an object of this invention to provide a lock in which removal of the cylinder is positively prevented as long as the cylinder is not turned beyond its normal limits of rotation, and 5 to provide novel means for defining the normal limits of rotation, which means may be disabled to allow rotation of the cylinder to a releasing position.

Another object of this invention is to provide 10 releasable means for defining the limits of rotation of the cylinder which may be released by a tool inserted endwise into the cylinder from the front end thereof.

A further object of this invention is to provide 15 means for positively holding the cylinder against withdrawal and for defining the normal limits of rotation of the cylinder, so associated that a single element is common to both of said means.

With the above and other objects in view which 20 will appear as the description proceeds, this invention resides in the novel construction, combination and arrangement of parts substantially as hereinafter described and more particularly defined by the appended claims, it being understood 25 that such changes in the precise embodiment of the hereindisclosed invention may be made as come within the scope of the claims.

The accompanying drawings illustrate one 30 complete example of the physical embodiment of the invention constructed according to the best mode so far devised for the practical application of the principles thereof, and in which:

Figure 1 is a view partly in side elevation and 35 partly in longitudinal section showing a lock embodying this invention;

Figure 2 is a front end view of the lock with parts broken away and the key in section;

Figure 3 is a cross sectional view taken through Figure 1 on the plane of the line 3—3;

Figure 4 is a view similar to Figure 1, but showing the manner of releasing the rotation limiting means;

Figure 5 is a cross section view similar to Figure 3, but with the cylinder turned to its withdraw- 45 ing position;

Figure 6 is a perspective view of the front end of the lock casing; and

Figure 7 is a perspective view of the cylinder looking forwardly from the rear end thereof.

Referring now particularly to the accompanying drawings in which like numerals indicate like parts throughout the several views, the numeral 5 designates a casing or mounting member which is bored as at 6 to receive a lock cylinder 7. The cylinder 7, is equipped with tumblers which en-

gage with a locking bar 7' and project the same into one of a pair of longitudinal grooves 8 formed in the wall of the bore 6 for securing the cylinder against rotation.

The tumblers are retractable within the cylinder by a key 9 insertable into the keyway 10. Upon retraction of the tumblers the cylinder is freed for rotation within predetermined limits defined in the manner to be hereinafter described, and as long as the cylinder is not turned beyond these limits, it is positively held against withdrawal from the cylinder.

The means for securing the cylinder against withdrawal comprises two circumferentially spaced lugs 11 extending radially in from the wall 15 of a counterbore 12 formed at the outer end of the casing and in which a head 13 on the cylinder is disposed, and a stop member 15 carried by the cylinder 7. The lugs 11 together form a shoulder or ledge in back of which two circumferentially spaced cylinder carried lugs 14 engage. 20 As long as any portion of the lugs 14 is engaged in back of the lugs 11, the cylinder is prevented from outward withdrawal, but upon being turned to a withdrawing position, as shown in Figure 5, 25 at which both lugs 14 are disengaged from the lugs 11, the cylinder is free for withdrawal.

The normal limits of rotation of the cylinder are defined by the engagement of the stop member 15 carried by the cylinder with the outer ends 30 16 and 17 of the lugs 11. The stop member 15 has a substantially T-shaped cross section and is axially slid able in a correspondingly shaped groove 18 formed in the front end of the cylinder, the stem of its T-shaped body projecting 35 from the cylindrical surface of the cylinder to contact with the ends of the lugs 16 and 17 in limiting the rotation of the cylinder.

An expansive spring 19 having its opposite ends received in pockets 20 and 21 formed respectively 40 in the bottom of the slot 18 and the inner end of the stop member yieldingly urges the stop member outwardly of the cylinder to its operative position. The forward motion of the stop member induced by the spring 19 is limited by the 45 engagement of the forward end of the stop member with the inner wall of a finishing cap 22 secured over the head 13 of the cylinder.

This cap has a hole 23 in line with the stop member through which a wire may be inserted 50 to push back the stop member out of circumferential alignment with the lugs 11 permitting the cylinder to be turned beyond its normal limits of rotation to a position shown in Figure 5. When so positioned, the stop member aligns with 55

the space 25 between the lugs 11 so that the cylinder may be withdrawn.

It is to be observed that the abutments or lugs 16 and 17 not only coat with the stop member 15 to define both of the normal limits of rotation of the cylinder, but also act to positively prevent withdrawal of the cylinder except when it is turned to its withdrawing position, and that the use of a proper key is necessary to effect withdrawal of the cylinder as the cylinder must be turned out of its locked position to place the same in its withdrawing position.

From the foregoing description taken in connection with the accompanying drawings, it will be readily apparent to those skilled in the art to which this invention appertains that this invention provides a simple and effective manner of removably securing a lock cylinder in its casing.

20 What I claim as my invention is:

1. In a lock, a bored casing, a cylinder rotatable therein between predetermined normal limits upon the insertion of a proper key, means for positively preventing withdrawal of the cylinder except when the same has been turned to a predetermined position which lies beyond said normal limits, and means for defining the normal limits of rotation of the cylinder comprising circumferentially spaced abutments on the casing, 25 and a yieldable stop member carried by the cylinder and normally retained in a position transversely aligned with said abutments to be engageable therewith and movable axially of the cylinder to free the cylinder for rotation beyond said limits of rotation.

2. In a lock, a bored casing, a lock cylinder rotatable therein, and means for defining the normal limits of rotation of the cylinder comprising spaced abutments carried by the casing and projecting inwardly from the bore thereof, and a yieldable stop member carried by the cylinder and normally held in a position transversely aligned with the abutments to be engageable therewith and movable inwardly in a direction parallel with the axis of the lock to free the cylinder for movement past its predetermined limits of rotation.

3. In a lock, a bored casing, a lock cylinder rotatable therein, and means for defining the normal limits of rotation of the cylinder comprising circumferentially spaced abutments projecting inwardly from the wall of the casing bore, and a movable stop member slideable axially in a slot in the cylinder with a portion thereof 50 projecting from the side wall thereof for coaction with said spaced abutments, a spring acting on the stop member to hold the same in its operative position at which it is aligned with spaced abutments, and a front wall for the cylinder closing the slot in the cylinder in which 55 said stop member slides to limit the move-

ment of the stop member by its spring, and said front wall having a hole through which a tool may be inserted for pushing the stop member inwardly out of alignment with the spaced abutments on the casing.

4. In a lock, a bored casing, a lock cylinder rotatable therein, and means for defining the normal limits of rotation of the cylinder comprising circumferentially spaced but transversely aligned abutments on the casing projecting in 10 from the wall of its bore, the cylinder having an undercut open slot in its front end portion opening to its side wall, a movable stop member slideable in said slot with a part thereof projecting from the cylinder side wall to cooperate with 15 the spaced abutments, and means yieldingly maintaining said stop member in its operative position from which it is movable to disalign the same with said spaced lugs and free the cylinder for rotation beyond its normal limits.

5. In a lock, a bored casing having a counterbore, a lock cylinder rotatable in the bore, a head on the cylinder disposed in the counterbore, means for defining the normal limits of rotation for the cylinder comprising circumferentially 25 spaced but transversely aligned lugs projecting in from the wall of the counterbore inwardly of the cylinder head, the cylinder having an undercut slot in its front end portion extending through the head and opening to the side of the cylinder, 30 a movable stop member slidably disposed in said slot and having a part projecting therefrom for coaction with the spaced abutments, a spring yieldingly urging the stop member outwardly toward the front of the cylinder, and a finishing shell covering the head of the cylinder and closing the open front end of the slot to limit the outward movement of the stop member by 35 its spring, and said shell having a hole through which a tool may be inserted for pushing the stop member inwardly to disalign the same with said spaced lugs and free the cylinder for rotation beyond its normal limits.

6. In a lock, a bored casing, a lock cylinder rotatable therein, a lug projecting inwardly from 45 the wall of the casing bore, a flange on the cylinder engaging in back of the lug to prevent withdrawal of the cylinder as long as the flange is engaged with said lug, said flange being disengageable from the lug upon rotation of the 50 cylinder to a predetermined position, and a releasable stop member normally transversely aligned with the lug to be engageable with the end of the lug for normally preventing rotation of the cylinder to said predetermined position, 55 said stop member being movable axially of the cylinder and transversely to the lug out of transverse alignment with the lug to free the cylinder for rotation to said predetermined position.

60 EDWARD N. JACOBI.
